UNITED STATES PATENT OFFICE

2,560,079

FOLDABLE SEAT AND UMBRELLA CASE

Paul Blum, Brooklyn, N. Y.

Application May 1, 1950, Serial No. 159,258

8 Claims. (Cl. 155--135)

1

The present invention relates to improvements in collapsible seats and more particularly to a collapsible seat and umbrella combination.

An object of the present invention is to provide a novel structure which is readily adapted to form a supporting seat and which is readily collapsible for positioning within a casing which is adapted to also house an umbrella.

Further objects of the present invention are to provide such means that are easily arranged in supporting position, easily collapsed to carrying position, economical of manufacture, and relatively simple.

Various other objects and advantages will be apparent from the detailed description to follow. In the description as well as in the claims, parts are at times identified by specific names for convenience, but such nomenclature is intended to be as generic in its application to analogous parts as the prior art will permit.

The best form in which I have contemplated applying my invention is illustrated in the accompanying drawings, wherein:

Figure 1 is a side elevational view of the present invention showing the carrying case with the seating structure collapsed therein;

Figure 2 is a perspective view of a portion of the present invention showing the collapsible seat in open position;

Figure 3 is a vertical transverse sectional view taken substantially along the plane of line 3--3 of Figure 1;

Figure 4 is a horizontal transverse sectional view taken substantially along the plane of line 4--4 of Figure 1;

Figure 5 is a vertical sectional view taken substantially along the plane of line 5--5 of Figure 2; and,

Figure 6 is a top plan view of Figure 5.

Referring more particularly to the drawings, wherein like numerals designate like parts throughout, numeral 10 designates generally the casing of the present invention, numeral 12 designates the seating structure, and numeral 14 designates a conventional umbrella.

The casing 10 is formed of a tubular portion 16 having a closed end 18 and an open upper exteriorly threaded end 22. Positioned on the lower or closed end 18 is a rubber-like suction cup or base portion 20 which is recessed at 21 for positioning about the lower end of the casing.

The upper portion of the casing 10 is formed from a multi-sided portion 24 having a reduced cross sectional end 26 which is threaded at 28 for securing on the upper end 22 of the tubular

2

portion 16. The upper end of the portion 24 is bent back upon itself at 28 to provide an open upper end 30. The upper portion 24 of the casing 10 is preferably formed with an octagonal cross section, and has each of its faces provided with stamped portions 32 having an upper tongue 34 bent inwardly, and a lower tongue 36 bent outwardly, as seen best in Figures 1 and 3. One of the faces 38 of the portion 24 is provided with a longitudinal slot 40 for a purpose to be hereinafter described.

Looking now at Figures 5 and 6, the seating structure will presently be described. The seating structure 12 is provided with a pair of octagonal rings, a lower one 42 and an upper one 44. The octagonal rings 42 and 44 are vertically spaced by an octagonal sleeve 46, each end of each face of the octagonal sleeve 46 having bifurcated hinge ends 48 and 50 for connection to the octagonal rings 42 and 44 respectively. The upper octagonal rings 44 have eight flat straps 52 having hinge ends 54 for connection to the ring 44. The flat straps 52 are provided with downwardly stamped portions 58 providing shoulders 25 for cooperation with supporting means, and have their ends formed in loops 60 for a purpose to be hereinafter described. The angular supporting struts 56 consist of flat straps having hinge ends 62 whereby the straps 56 may be mounted on the octagonal ring 42.

Each of the horizontal seating straps 52 is provided with a plurality of pairs of apertures 64. An outer strengthening cord 66 is passed through the looped ends 60 of each of the flat straps 52 forming the outer circumstance of the seating structure 12. An inner supporting cord 68 is passed through the innermost set of apertures 70, and has its ends secured together in any conventional fashion. A plurality of concentric supporting cords 74 are passed through the radially spaced pairs of apertures 76. A plurality of radially disposed tying cords 72 are secured to the outer cord 66 and inner cord 68 to complete the seating portion.

Looking now at Figures 3 and 4, the purpose of the slot 40 will be described. An actuating pin 78 is fixedly secured to the spacer 46, has a spacer washer 80 mounted thereon, and a locking screw 82 for securing the vertical spacer 46 in either its upper or lower position.

As seen in Figures 1 and 3, the seating structure 12 is in collapsed position within the upper open receiving end 24 of the casing 10. The nut 82 on the threaded pin 78 is secured in the lowermost position of the slot 40 and a con-

ventional umbrella 14 is positioned within the hollow casing, so that the entire device may readily be carried by the strap 84 secured by the pin 86 to the casing 16. When it is desired to provide a seat for supporting a person desiring to observe sporting events, parades, and the like, the nut 82 is loosened and moved to its uppermost position in the slot 40 and secured. It will readily be seen that as the pin 78 is moved upwardly, the spacer 46 will move upwardly therewith carrying the flat straps 52 and supporting straps 56 similarly upward. When the upper ends 88 of the supporting straps 56 engage the inwardly extending tongue 34, they will be projected outwardly from the upper portion of the casing 24 being pivoted about the lower octagonal ring 42 and bearing against the outwardly extending tongue 36. At the same time, the flat straps 52 will be pivoting about the upper octagonal ring 44 and bearing downwardly against the upper lip 28 of the casing portion 24. At the same time the flat straps 52 reach a horizontal position, bringing the cords to a taut arrangement, the upper ends 88 of the supporting members 56 will engage the downwardly projecting lips 58, whereby the entire seating portion 12 may be supported. The nut 82 will then be secured in its uppermost position.

By constructing the present invention from hollow tubular material, a convenient storage casing is provided for a conventional umbrella 14, so that an umbrella is conveniently at hand in the case of inclement weather.

From the foregoing, it will readily be seen that I have provided a novel device which is readily adapted to be opened up to provide a seat at the carrier's will. It will be noted that the number of horizontal supporting straps 52 depends upon the number of sides which the rings 44 and 42 are provided with. It will therefore be seen that the number of horizontal supporting straps 52 may be varied by providing rings having different numbers of sides as desired.

The cord used in the present invention may be formed of any of the conventional materials available on the market.

Some changes may be made in the construction and arrangement of the parts of my device without departing from the real spirit and purpose of my invention, and it is my intention to cover by my claims any modified forms of structure or use of mechanical equivalents which may be reasonably included within their scope without sacrificing any of the advantages thereof.

Having thus described my invention, what I claim to be new is:

1. A combination collapsible seat and umbrella holder comprising a hollow casing having a support base and an open upper end, means receivable in said open upper end adapted to be positioned to provide a seat when in a second position, means for supporting said first mentioned means when in said second position, said first mentioned means comprising a plurality of flat straps hingedly connected to a multi-sided ring reciprocable in said casing, means for moving said ring to an upper position whereby said straps are free to pivot to a horizontal position, and said second named means engageable with the outer portions of said straps to provide supports therefor.

2. A combination collapsible seat and umbrella holder comprising a hollow casing having a support base and an open upper end, means

receivable in said open upper end adapted to be positioned to provide a seat when in a second position, means for moving said first mentioned means from collapsed position in said casing to said second position, means for supporting said first mentioned means when in said second position, said first mentioned means comprising a plurality of flat straps hingedly connected to a multi-sided ring reciprocable in said casing, and cord means interwoven with said flat straps to provide the seat.

3. A combination collapsible seat and umbrella holder comprising a hollow casing having a support base and an open upper end, means receivable in said open upper end adapted to be positioned to provide a seat when in a second position, means for supporting said first mentioned means when in said second position, said first mentioned means comprising a plurality of flat straps hingedly connected to a multi-sided ring reciprocable in said casing, means for moving said ring to an upper position whereby said straps are free to pivot to a horizontal position, said second named means engageable with the outer portions of said straps to provide supports therefor, and cord means interwoven with said flat straps to provide the seat.

4. A combination collapsible seat and umbrella holder comprising a hollow casing having a support base and an open upper end, annular means receivable in said open upper end adapted to be positioned to provide a seat having a central opening when in a second position, means for supporting said first mentioned means when in said second position, and said hollow casing and annular means providing an umbrella receiving case whereby an umbrella can be inserted through said open end and annular means for positioning in said case.

5. A combination collapsible seat and umbrella holder comprising a hollow casing having a support base and an open upper end, means receivable in said open upper end and adapted to be positioned to provide a seat when in a second position, means for supporting said first mentioned means when in said second position, said first mentioned means including a multi-sided sleeve, a plurality of flat straps hingedly connected to the upper and lower ends of said sleeve, said casing having slots for slidably receiving the straps connected to the lower end of said sleeve, the straps connected to the upper end of said sleeve having shoulders formed thereon for receiving the outer ends of the straps connected to the lower end of said sleeve when in said second seat forming position.

6. A combination collapsible seat and umbrella holder comprising a hollow casing having a support base and an open upper end, means receivable in said open upper end and adapted to be positioned to provide a seat when in a second position, means for supporting said first mentioned means when in said second position, said first mentioned means including a multi-sided sleeve, a plurality of flat straps hingedly connected to the upper and lower ends of said sleeve, said casing having slots for slidably receiving the straps connected to the lower end of said sleeve, the straps connected to the upper end of said sleeve having shoulders formed thereon for receiving the outer ends of the straps connected to the lower end of said sleeve when in said second seat forming position, and means for slidably effecting raising and lowering movement of said sleeve with respect to said casing.

7. A combination collapsible seat and umbrella holder comprising a hollow casing having a support base and an open upper end, means receivable in said open upper end and adapted to be positioned to provide a seat when in a second position, means for supporting said first mentioned means when in said second position, said first mentioned means including a multi-sided sleeve, a plurality of flat straps hingedly connected to the upper and lower ends of said sleeve, said casing having slots for slidably receiving the straps connected to the lower end of said sleeve, the straps connected to the upper end of said sleeve having shoulders formed thereon for receiving the outer ends of the straps connected to the lower end of said sleeve when in said second seat forming position, and means for selectively positioning said sleeve in its lower and second positions.

8. A combination collapsible seat and umbrella holder comprising a hollow casing having a support base and an open upper end, means receivable in said open upper end and adapted to be positioned to provide a seat when in a second po-

10
5

sition, means for supporting said first mentioned means when in said second position, said first mentioned means including a multi-sided sleeve, a plurality of flat straps hingedly connected to the upper and lower ends of said sleeve, said casing having slots for slidably receiving the straps connected to the lower end of said sleeve, the straps connected to the upper ends of said sleeve having shoulders formed thereon for receiving the outer ends of the straps connected to the lower end of said sleeve when in said second seat forming position, and cord means interwoven with the upper straps to provide a seat.
